UNITED STATES PATENT OFFICE.

MAXIME LEBLANC, OF MONTREAL, CANADA.

STAIR-MARKING TOOL.

No. 811,233.

Specification of Letters Patent.

Patented Jan. 30, 1906.

Application filed June 5, 1905. Serial No. 263,691.

To all whom it may concern:

Be it known that I, MAXIME LEBLANC, a subject of the King of Great Britain, residing in the city and district of Montreal, in the Province of Quebec, Canada, have invented certain new and useful Improvements in Stair-Marking Tools; and I do hereby declare that the following is a full, clear, and exact description of the invention, such as will enable others skilled in the art to which it appertains to make and use the same.

This invention relates to new and useful improvements in combination-tools adapted especially for use in marking the runners of stairs to furnish guides from which channels are cut in said runners for the treads and risers comprising the steps.

The object of the invention is to provide a simple, compact, and easily-adjusted tool which is especially adapted for use in marking stairs, which may be so adjusted that the angle with relation to the tread and the riser may be varied, and includes a reversible marking-plate adapted to serve as a guide in marking the channel for the tread of varying widths.

The invention consists in the combination and arrangement of parts which are shown in the accompanying drawings, all as hereinabove more fully described, and particularly pointed out in the claims, it being understood that said drawings illustrate the preferred construction, which may be departed from in the form, proportion, and minor details of parts therein shown within the scope of the claims without sacrificing any of the advantages of the invention.

In the accompanying drawings, in which similar characters of reference indicate corresponding parts in all the views, Figure 1 is a plan view of the complete tool ready for use. Fig. 2 is a section on line 2 2 of Fig. 1 looking in the direction of the arrow. Fig. 3 is a section on line 3 3 of Fig. 1 looking in the same direction. Fig. 4 is a detached view of the pivoted plate hereinafter referred to. Fig. 5 is a detached view of the slidable plate hereinafter referred to. Fig. 6 shows a stair-runner or end piece which is provided with channels for the tread and riser in a portion thereof, showing in the same view a section of a tread and riser in position with locking-wedges properly placed and at the upper portion of said view the manner of applying the tool for the purpose of marking the outlines of the channel for said tread and riser. Fig.

7 is a detached view of the jointed marking-tool detached from the marking-plates, showing how it may be used as a divider. Fig. 8 shows the jointed marking-tool locked in position for use as a square. Fig. 9 is a detached detail view of the filler-block, hereinafter referred to, which is used to complete the rectangle at the corner of the square shown in Fig. 8. Fig. 10 is a section on line 10 10 of Fig. 1.

Referring to the parts, 1 is a marking-tool comprising the pivotally-connected arms 2 and 3, the arm 2 having secured to it a serrated or notched segment 4, which is provided with an indicating-scale 5 and with a plurality of notches or recesses 6, with which notches the finger 7 of the rockable spring-actuated locking-dog 8 is adapted to engage, a spring 9 bearing against the under side of said locking-dog for the purpose of throwing said finger 7 inwardly to engage with the notches 6 referred to.

Pivots connected with the arm 2 is the filler-block 10, which filler-block has extending laterally therefrom the stop 11, which stop is adapted to rest against the upper end of the arm 3, as shown in Fig. 8, or rest in the recess 12 (shown in said Fig. 8) when the tool is not to be used as a square—as, for example, as shown in Fig. 7.

Coöperating with the locking-dog 8 is a setscrew 13, which is held in the screw-threaded block 14, which block is mounted on the setscrew 13 and bears at its inner end against the segment 4, so that said segment may be locked in any position intermediate the notches 6 by means of said screw when desired.

The arms 2 and 3 are provided with longitudinal slots 16 and 17, respectively, and pivotally connected with the arm 3 by means of the laterally-projecting pin 18 is a marking-plate 19, which is shown detached in Fig. 4. Said plate 19 is provided at opposite ends with said pins 18 and perforations 20, which perforations are arranged approximately centrally of the arc formed by the ends of said member 19. This plate 19 is slotted longitudinally at 21, as shown. The arm 3, in addition to the slot 17, is provided with a shorter longitudinally-extending slot 22, into which projects the pin 23, carried by the slidable plate 24, which plate 24 is also longitudinally slotted, as shown at 25. It will be observed that the plate 24, like the plate 19, is wider at one end than at its opposite end, and when

the plates 19 and 24 are placed in position, as shown in Fig. 1, the adjacent edges thereof extend slightly beyond the inner edges 25 and 26 of the arms 2 and 3.

Extending from the arm 2 to the arm 3 is a diagonal telescopically-arranged connecting member comprising the flanged and longitudinally-slotted plate 28 and the extension 29, both said plate 28 and extension 29 being longitudinally slotted, as shown at 30 and 31, respectively. Connecting the plates 28 and 29 and slidably in the slots thereof is a screw 32, which is provided for well-understood purposes. Connecting the plate 28 with the arms 2 is a set-screw 34, a similar screw 35 being provided to connect said plate 28 with the plate 19, and said set-screws 34 and 35 are projected, respectively, through the slots 16 and 21 and a slot 36, formed in the end portion of said plate 28. Projecting through the slots 17, 25, and 31 is a set-screw 37, which serves to connect the extension 29 and the arm 3 with the slidable plate 24, so that when it is desired to change the angle of relation between the arms 2 and 3 and their corresponding plates 19 and 24 the set-screws referred to will travel in the longitudinal slots referred to, and when the tool has been adjusted to the desired angle said set-screws 30 may be tightened to lock it in position. As the set-screw 34 travels through a different arc from that of the set-screw 35, the plate 19 is preferably cut away at 39, as shown in Fig. 5, and to utilize this cut-out portion scrolls 40 are formed, which may be used to mark the outline of moldings which are used for ornamentation in buildings. The plate 28 is provided, as described, with a laterally-projecting flange 41, (best shown in Fig. 10,) which 40 flange is adapted to serve as a guide in using the tool.

When the tool is in use as a stair-marking tool, said flange 41 rests against the edge 42 of the runner 43, and the outer edges of the arms 2 and 3, together with the inner or adjacent edges of the plates 19 and 24, serve as guides for the pencil to be used in marking the tread-channel 44 and riser-channel 45, which channels are preferably made wider at 45 one end for the insertion of the wedges 46, which wedges are adapted, respectively, to force the tread 47 upwardly against the upper face of the channel 44 and to force the riser 48 outwardly against the outer edge of 50 the channel 45. To assist in forming the channel 44, the perforations 20 are provided in the end portions of said plate 19, and as said perforations 20 are relatively centrally 55 of the arc formed by the ends of said plate 19 60 it is evident that the pencil-point may be projected through said perforations 20 to mark the center to be used as a guide in boring the runner 43 to provide the curved outer end portion 50 of the tread-channel 44. If it is 65 desired to form the channel 44 of less width

than would be formed when the tool is in the position shown in Fig. 1, the plate 19 may be reversed and the pin at the opposite end thereof may be projected through the perforation in the arm 3 to place said plate in position to form a tread-channel of less width, in which case the lower edge of said plate 19, as shown in Fig. 1, will rest nearer to the edge 25 of the arm 2, and when the tool is used in this position a tread-channel of less width 75 may be marked.

To adapt the tool for use as a square, said filler-block 10 is provided, which is preferably rectangular at two of its edges, as best shown in Fig. 8, so that said filler-block will 80 serve as a means for completing the square formed by the outer edges of the arms 2 and 3 when said filler-block is thrown to a position so that the stop 11 thereof will rest against the upper edge of the arm 3. 85

The tool is adapted for purposes other than described, and it is evident that the arms 2 and 3 may be adjusted to occupy any angle within the compass of the segment 4, and having the pointed ends 51 formed on said 90 members 2 and 3 it is evident that the tool when the plates 19 and 24 are detached may be used as a pair of dividers, as shown in Fig. 7, the points 51 serving as marking-points, if desired. 95

When the plate 19 is placed in a reversed position to that shown in Fig. 1, it is evident that owing to the position of the pin 18 in the narrow end of said plate the inner edge thereof will rest at a distance from the upper edge 100 24^a of the plate 24, in which case said plate 24 may be slid longitudinally of the arm 3, the pin 23 riding in the slot 22 until said edge 24 contacts with the lower edge of the plate 19, after which said plate 24 may be locked in 105 position.

Having described my invention, what I claim, and desire to secure by Letters Patent, is—

1. In a stair-marking tool, a pair of pivotally-connected members, means for locking them in different angular relations to each other, longitudinally-slotted plates connected with each of said members, and an obliquely-extending arm connecting said pivotally-connected members and said plates. 110

2. In a stair-marking tool, a pair of longitudinally-slotted pivotally-connected members, means for locking them in different angular relations to each other, longitudinally-slotted plates connected with each of said members, locking means therefor, and an obliquely-extending arm connecting said pivotally-connected members and said plates. 120

3. In a stair-marking tool, a pair of pivotally-connected members, means for locking them in different angular relations to each other, longitudinally-slotted plates connected with each of said members, one of which is slidably longitudinally, and an obliquely-ex- 125 130

tending arm connecting said pivoted members and said plates.

4. In a stair-marking tool, a pair of pivotally-connected members, means for locking them in different angular relations to each other, longitudinally-slotted plates connected with each of said members, an obliquely-extending longitudinally-slotted telescoping arm connecting said pivoted members and said plates, and locking means slidable in the slots in said arm.

5. In a stair-marking tool, a pair of pivotally-connected members, means for locking them in different angular relations to each other, longitudinally-slotted plates connected with each of said members, one of said plates being wider at one end than at its opposite end, the other of said plates being slidably longitudinally, slotted, slidable connecting members, and locking means adapted to travel in the slots of said connecting members.

6. In a tool of the character described, a jointed marking member comprising a pair of pivotally-connected and longitudinally-slotted arms, plates wider than said arms connected therewith, one of said plates having a perforated extension projecting beyond the joint, and means adapted to secure said marking member and said plates in a plurality of positions.

7. In a tool of the character described, a jointed marking member comprising a pair of pivotally-connected and longitudinally-slotted arms, plates wider than said arms connected therewith, one of said plates having a perforated extension projecting beyond the joint, said plate being reversible and being wider at one end than at its opposite end, and means adapted to secure said marking member and said plates in a plurality of positions.

8. In a stair-marking tool, a pair of pivotally-connected members, a pivot therefor, means for locking said pivoted members at different angles to each other, a longitudinally-slotted plate pivotally mounted on one of said pivoted members, and means for locking said plate in position.

50 9. In a stair-marking tool, a pair of pivotally-connected members, a pivot therefor, means for locking said pivoted members at different angles to each other, a longitudinally-slotted and perforated plate pivotally mounted on one of said pivoted members, and means for locking said plate in position, the perforated portion of said plate extending beyond the said pivot.

10. In a stair-marking tool, a pair of pivotally-connected members, a pivot therefor, a pair of plates connected with and extending

substantially parallel with said pivoted members, one of said plates being wider at one end than at its opposite end and extending beyond said pivot, and means for locking 65 said movable parts in a plurality of positions.

11. In a stair-marking tool, a pair of pivotally-connected members, one of said members having a longitudinally-extending slot therein, the other of said members having a 70 plurality of slots, an approximately parallel plate pivotally connected with one of said members, there being a longitudinal slot in said plate extending parallel with the other of said pivoted members, a pin projecting 75 from said last-mentioned plate into a slot in its companion pivoted member, and means for locking said parts in a plurality of positions.

12. In a stair-marking tool, a pair of pivotally-connected members, a pivot therefor, a segment connected with one member, locking means on the other member adapted to engage said segment, and a rectangular filler-block pivotally mounted in proximity to said 85 pivot.

13. In a stair-marking tool, a pair of pivotally-connected members, a pivot therefor, a segment connected with one member, locking means on the other member adapted to 90 engage said segment, and a rectangular filler-block pivotally mounted in proximity to said pivot, there being a laterally-extending stop on said filler-block.

14. In a stair-marking tool, a pair of pivotally-connected and longitudinally-slotted members, a pivot therefor, a longitudinally-slotted and perforated plate mounted upon one of said pivoted members, said plate extending beyond said pivot, a longitudinally-slotted plate mounted upon the other pivoted member, and locking means adapted to hold 95 said pivoted members and said plates in different angular relations.

15. In a stair-marking tool, a pair of pivotally-connected and longitudinally-slotted members, a pivot therefor, a longitudinally-slotted and perforated plate mounted upon one of said pivoted members, said plate extending beyond said pivot, a longitudinally-slotted plate mounted upon the other pivoted member, locking means adapted to hold said pivoted members and said plates in different angular relations, and a laterally-extending pin projecting from said last-mentioned plate 100 into a slot in its companion pivoted member. 110 115

In witness whereof I have hereunto set my hand in the presence of two witnesses.

MAXIME LEBLANC.
